ATTORNEY

UNITED STATES PATENT OFFICE

HENRY SAHLMANN, OF BROOKLYN, NEW YORK

ROLLER SKATE

Application filed May 28, 1928. Serial No. 281,005.

This invention relates to a roller skate in which the rollers of the skate are all placed in alignment.

The usual roller skate has four rollers rect-
5 tangularly positioned on the skate. Such an arrangement, as is well known and obvious, is not as effective in turning as the single runner used on ice skates.

It is accordingly an object of this invention to provide a roller skate embodying some of the principles of an ice skate to enable greater speed and ease in turning.

It is a further object of the invention to provide a roller skate which may be easily 15 and cheaply made and will be as strong and durable as roller skates of the common type.

These and other objects are attained by the novel construction, combination and arrangement of parts, hereinafter described 20 and shown in the accompanying drawing, constituting a material part of this disclosure, and in which:—

Figure 1 is a side view of the skate.

Figure 2 is a bottom view of the skate.

25 Figure 3 is a rear view of the skate.

Figure 4 is a view taken along line 4—4 of Figure 1.

Referring to the drawings, the skate is shown to comprise a plate 5 which is adjust- 30 ably connected to the toe-plate 6 by means of a screw threaded bolt and wing nut 7, and the plate 5 has integral therewith a heel guard 8. The toe-plate 6 has mounted thereon the clamping members 9 which are controlled by the threaded bolt 9', this structure being common in roller skates.

Riveted to the under sides of plates 5 and 40 6 are the supports 10, 11 and 12, each of which is flared at its lower extremity to form a jaw 16 adapted to embrace the tubular portion 15 of the roller bracket having the vertical side portions 14. In assembling the 45 skate, the jaw 16 is slid over the tubular portion 15 and then the sides of the jaw are pressed tightly around the portion 15 to securely hold the latter, as shown in Figure 3.

A plurality of rollers 17, 18, 19, 20 and 21 are mounted in the roller bracket between the sides 14 by means of the bolts 22 and nuts 50 22' and 22'', the bolt being surrounded by a

spacing member 25 which prevents frictional contact between the rollers and the sides 14, the rollers being rotatably mounted on the members 25.

In the skate shown in Figure 1, five rollers are used, one of the rollers being mounted in the inclined portion of the roller bracket, thus simulating the ice skates as far as possible.

From the above description it will be seen 60 that there has been provided a simple roller skate which obviously is more efficient in operation than the common roller skate in which the rollers are rectangularly positioned. The rollers in alignment facilitate 65 turning movements and the inclined portion of the roller bracket enables the performance of stunts which heretofore was impossible with the usual roller skate.

The foregoing disclosure is to be regarded 70 as descriptive and illustrative only and not as restrictive or limitative of the invention, of which obviously an embodiment may be constructed, including many modifications, without departing from the general scope 75 herein indicated and denoted in the appended claim.

Having thus described my invention, what I claim as new and desire to secure by Letters Patent, is:—

A roller skate having a foot supporting plate, supports fixed to the underside of said plate, said supports having jaws at their lower ends, a roller bracket having a tubular portion gripped by the jaws on the supports, 85 said bracket having vertical side portions, spacing members positioned between said side portions, and rollers rotatably mounted on said spacing members, said rollers being in alignment.

In witness whereof I have affixed my signature.

HENRY SAHLMANN.
